Patented Apr. 26, 1927.

1,626,305

UNITED STATES PATENT OFFICE.

ROBERT STEPHENSON, OF BLACKBURN, ENGLAND.

GARMENT SUSPENDER.

Application filed May 1, 1926, Serial No. 106,041, and in Great Britain May 22, 1925.

This invention relates to garment suspenders especially for stockings, socks and the like and has for its object to provide a suspender having a minimum number of 5 parts which can be assembled without stitching or like means.

As a rule, the portion of a suspender which actually engages the stocking or sock comprises a metal clip in the form of a plate 10 having a key-hole slot therein, adapted to engage a rubber stud or button formed on or connected to a tag of rubber or the like. Hitherto the upper end of the slotted metal plate has been connected to the tag by means 15 of a loop of elastic or fabric or it has been carried by a separate tag which lies above that which carries the rubber stud.

According to this invention the tag which carries the stud is provided with lateral slots 20 so that it can be sprung into engagement with arms or trunnions formed on the back of the slotted plate about which the plate can then pivot. The plate is preferably pressed from sheet metal, celluloid or other 25 suitable material.

When the invention is applied to a sock suspender of the known triangular pad type, the entire pad together with the strap portion which encircles the leg may be formed 30 from a single piece of rubber, the pad not only having at its lower extremity a slotted tag carrying a stud as already described, but also being furnished with one or more additional and similar studs to engage holes in 35 the strap portion and with one or more slots through which the free end of the strap may be passed so as to lie between the pad and the wearer's leg.

One construction of sock suspender embodying the present invention is shown by 40 way of example in the accompanying drawings in which—

Figure 1 is an elevation showing the suspender without the metal clip,

Figure 2 is a sectional elevation of the pad showing the clip in its closed position.

Figure 3 is a perspective view of the metal clip detached, and

Figure 4 is a section on the line 4—4 of 50 Figure 1.

The suspender illustrated comprises a substantially triangular rubber pad portion A having a strap portion B formed in one with it, if desired one or both these parts being 55 provided on their rear face with ribs or corrugations such as A¹ (Figure 4) to ensure

ventilation. The lower end of the pad carries a stud C the neck of which has a reinforcing web C¹ adapted to engage the sock in the known manner.

A similar stud D is provided at the upper corner of the pad opposite the strap portion and, if desired, an identical stud E may be formed on the face of the pad at the junction between the pad and the strap. 60 When an additional stud E is provided, the strap can, at the option of the wearer, be severed from the pad along the dotted line B¹. The strap portion is furnished with a set of perforations D¹, which can engage 65 the stud D after the strap has been passed round the wearer's leg, the free end being then inserted through the slot A². If the strap portion is to be severed from the pad, an additional set of perforations E¹ are provided 70 one of which is caused to engage the extra stud E.

The metal portion of the clip comprises a single metal plate having a key-hole portion F, the reduced end of which engages 80 the stud C after the sock has been inserted between them in the usual manner. Instead of the clip being pivotally connected to the pad by means of an elastic loop or tag in the usual way, the plate has rearwardly 85 extending arms F¹ projecting at right angles to its main portion which constitute pivots or trunnions adapted to engage slots A³ formed in the edges of the pad, at their inner ends these arms being extended upwards and connected together by a transverse member F². Further, the main portion has arms F³ which extend towards the 90 centre of the tag, as clearly shown in Figure 3.

The shape of the complete metal plate is such that the tag can be sprung into engagement therewith and when so engaged the rearwardly extending arms F¹ form pivots about which it can turn and the rear transverse member F² and front arms F³ limit 100 this pivotal movement and prevent the clip being detached from the tag.

Hence, in its simplest form, a sock suspender according to this invention comprises 105 only two separate components—one of rubber and one of metal—each of which can be simply made and which can be instantly assembled without the aid of stitches, rivets or the like.

It is to be understood that though primarily designed for a sock suspender of

the pad type having an integral pad and strap, the metal clip and its cooperating rubber stud and integral supporting tag may be applied to other forms of suspender and that, if desired, a strap or garter of elastic, leather or fabric, separate from the pad, may be used without departing from the invention.

What I claim as my invention and desire 10 to secure by Letters Patent is:—

1. In a garment suspender the combination of a resilient tag having lateral slots 15 therein, a stud on the face of the tag and a separable clip member comprising a loop portion adapted to cooperate with the stud and having arms to engage the slots in the

tag in a removable manner so as to constitute pivots about which the clip can then pivot as set forth.

2. In a garment suspender the combination 20 of a resilient tag having lateral slots therein, an integral stud on the face thereof and a separable clip member formed from a single plate of substantially rigid material and comprising a loop portion adapted to 25 cooperate with the stud and having arms to engage the slots in the tag in a removable manner so as to constitute pivots about which the clip can then pivot as set forth.

In testimony whereof I have signed my 30 name to this specification.

ROBERT STEPHENSON.
